TYPEWRITER ACTION

Andrew F. Mulhare, Glenbrook, Conn.

Refiled for abandoned application Serial No. 581,149, August 11, 1922. This application July 7, 1934, Serial No. 734,098

15 Claims. (Cl. 197—27)

The present invention relates to an improvement in the "action" or mechanism of a typing machine by which the printing is effected, and has for its principal object the provision of a novel, simple and reliable construction of key levers, type bar, type bar connections and mounting for the same in a combination and arrangement whereby a substantially uniform movement of the finger keys will produce an accelerated movement of the type bars, thus obtaining a crisp and effective stroke with a prompt return of each type bar.

My improved mounting for the connections between key levers and type bars insures uniform action of the various type bars, and lends itself to prompt and easy assembling of parts. A further important advantage is found in the fact that my construction makes it possible to obtain direct and uniform connection between the parallel finger key levers and the series of cylindrically nested type bars at the end and intermediate positions as well as in the middle; and this is accomplished in my preferred construction by means of key levers interchangeably constructed throughout any one bank or row. Further advantages of the invention will become evident hereinafter.

The invention is illustrated in a preferred form in the accompanying drawings, wherein Figure 1 is a longitudinal sectional view of a part of a typing machine, showing one set of key levers and type bars in elevation together with a sufficient portion of the remainder of the machine to make the operation of my invention clear; Figure 2 is a sectional view of certain details of mounting; Figures 3 and 3a are respectively a partial plan view and an end elevation of the guide block for mounting the connecting bars; Figure 4 is a front elevation of the entire machine, certain parts being shown in section on the line 4—4 in Figure 1; and Figures 5 and 5a are identical parts of any two key levers in the same bank or row.

The framework of the machine, shown at 10, supports the platen 11 on the usual carriage 12, as well as a set of type bars 13, nested in a well known manner in front of the platen. Each of the type bars has a rearward extension or arm 14 formed with a slot 15, as clearly shown in Figure 1.

The finger key levers 16 are made of thin metal, and are normally supported as shown in Figure 1. A straight fulcrum bar 17 is mounted in a bracket 18 at the rear of the frame, and extends from one side to the other of the same. Each finger key lever 16 is notched at its rear end, on its upper edge, and each notch is fitted over the

fulcrum bar 17, being held up against the same, as by the spring 19, which spring also keeps the forward upper edge of the bar normally in contact with the stop cushion 20.

Power is transmitted from each finger key lever 16 to its corresponding type bar 13 by a swinging connecting bar or lever 21, preferably stamped out of sheet metal. Each lever 21 carries a pin or roller 22 at its upper end which engages the slot 15 in the extension 14 of the type bar, and a second pin or roller 23 at its opposite end engages a cam slot 24 cut or stamped in the key lever.

The upper edge of the slot 24 is shaped upon a curve, so calculated and arranged that, when the lever 16 is depressed, this edge acts as a cam upon the pin 23, forcing it to move toward the right in Figure 1, while sliding along said curved edge. This swings the upper end of the lever 21 to the left in Figure 1, and the pin 22 is thus caused to slide along the front edge of the slot 15, while forcing the same forward, and causing the type bar 13 to swing rapidly upward and against the platen 11. As the upper arm of the lever 21 is longer than the lower arm, and, as the forward extension of the type bar 13 is longer than the extension 14, the full ninety degree swing of the type bar will be accomplished by quite a small angular movement of the lower arm of the lever 21. Owing to the shape of the operating cam edge of the slot 24, this small angular movement of lever 21 will be accomplished by a still smaller swing of the key-lever 16.

It will be seen that, by using a roller or pin (22, 23) at each end of each lever 21 and by fitting it closely to the two sides or edges of the slots (15, 24) through which the pins project, the movements of the type-bars 13 are confined, and all looseness is avoided and the position of each type bar is always controlled positively by the finger key lever, thereby producing a perfect impression on each stroke without danger of rebound with a consequent "shadow" impression. This arrangement also causes the key lever springs 19 to aid in producing the return of the type bars immediately after each impression is made. Furthermore, since each pin (22, 23) is constantly in contact with the operating edge of the corresponding slot, there is always a smooth action with a minimum of noise and wear.

To obtain the maximum effectiveness in an arrangement of the kind described, wherein the type bars 13 swing through ninety degrees, the shorter arm 14 of each type bar should swing through forty-five degrees on each side of the plane in which the type bar bearings lie; and in

the embodiment illustrated, each of these forty-five degree angles of the type bars 13 is produced by a swing of less than fifteen degrees of the longer arms of the levers 21, i. e., less than thirty degrees for the full swing of ninety degrees of the type-bars 13. At the same time the two arms of the levers 21 make such an angle with each other that the shorter arms describe the total angle of somewhat under thirty degrees or less upon occurrence of a depression of the key-levers which is uniform for all the key levers, which depression is determined by the form of the operating cam slot 24.

If the velocity of each lever 21 were uniform throughout each swing, in the arrangement shown, the fact that the pin 22 first approaches and then departs from the type bar bearing, would produce at first an accelerating and then a decelerating swing of the type bar, which would be the opposite of desirable. I, therefore, prefer to so shape the operating curve of the slot 24 in each finger key lever 16 that the forward swing of the connecting lever 21 will be accelerated to such a degree as to overcome the effect above noted, and will produce, on the contrary, a material acceleration of the type bar 13, especially toward the end of its movement. This gives a snappy stroke and return action, which conduce to excellence of impression. By arranging the pin 23 to swing through a relatively small angle in the lower part of its circular arc of movement, as shown, the variation in the effective leverage of the lower (shorter) arm of lever 21 is minimized, and the exact degree of acceleration desired is easily produced by suitably calculating the curve of the cam slot 24.

Another of the important features of my present invention is found in the special mode of mounting the swinging connecting levers 21, so that they can be readily assembled, and, at the same time, be perfectly aligned and guided, while accommodating their action to the usual semi-circular nesting of the type bars shown in Figure 4.

For this purpose, a supporting guide block 25 is provided, which extends from side to side across and over the key levers 16. As shown in Figure 4, this block 25 is provided with a slot for the fulcrum-rod 29 which is curved downward (preferably on the arc of a circle having a radius of about eighteen inches) and the block is conveniently supported by lugs 26, removably secured to a part of the frame 10, as by screws 27. Referring to Fig. 1 in which a type-bar 13 at the middle of the nest and its related key-lever 16 and connecting-lever 21 are shown, the two arms of lever 21, upon depression of the key-lever 16, are moved through angles of somewhat less than thirty degrees in producing a movement of ninety degrees of type-bar 13, from the position shown, to a printing position in front of the platen 11. The levers 21 from the middle of the nest toward each end produce movements of ninety degrees of the type bars 13, for equal depressions of the key levers 16 by movements through progressively less than thirty degrees, as hereinafter explained.

The rearward portion of the block 25 is cut to form as many parallel vertical guide slots 28 as there are connecting levers 21, and each lever 21 is slipped into one of these slots, where it is supported by a bearing rod or wire 29 which is passed through holes or openings 30 pierced in the connecting levers 21. These last named

openings 30 are countersunk from each side, as shown in Fig. 2, in order that the connecting levers 21 may turn freely on the fulcrum rod 29, and may swing freely each in its own vertical plane, determined by the contact between the flat sides of the levers 21 and the sides of the slots 28 in which these levers turn. The opening in the block 25 for the fulcrum-rod 29 is preferably in the form of a groove or slot 25' (Fig. 3a) running into said block from its upper face. When the parts are assembled, the fulcrum-rod 29 rests against the bottom of said slot.

The wire 29 (shown in dotted lines in Fig. 4) is curved on the arc of a circle corresponding to the curve of the slot 25' in block 25, so that this wire or rod may readily be threaded through the holes in the levers 21 and slid along the bottom of the slot 25' in the block 25.

As shown in Fig. 4, owing to the semi-circular nesting of the type bars 13, the upper arms of the connecting levers 21 furthest from the middle of the machine are bent inward considerably, and are necessarily much longer than those at the middle. This bending and this excess of length diminish gradually as the middle is approached. In order that a given or certain amount of depression of a key of one key-lever 16 may produce the same speed and acceleration of its type bar as is produced by the same amount of depression of every other key, the successively longer connecting levers 21 must be so mounted as to preserve a constant ratio between their two arms on opposite sides of their respective fulcrums on rod 29. It is a part of the arrangement for accomplishing this purpose that the bearing rod or wire 29 is curved as shown and described. Moreover, by reason of the progressively increasing lengths of the arms of connecting levers 21, from the middle position toward the end positions 40 of the nested levers, the angles which these arms make with vertical planes at and lengthwise of rod 29 at the respective points of bearing on rod 29 of the connecting levers, are progressively less from the middle position to the end positions, 45 so that the distance traversed or amount of movement described by the pins or rollers 22 will be equal to the lengths of the arcs of movement (ninety-degrees) of the arms 14 of type-bars 13, and therefore equal among themselves. 50

As illustrated in Figures 1, 3, and 3a, the curve upon which the rod 29 and the supporting guide block 25 is struck, does not occupy a vertical plane, but the plane which comprehends this curve is inclined slightly backward from the vertical, so that the lowest (middle) point is a little forward of the two ends. 55

In practice it is found that this inclination of the plane in which the curve of rod 29 lies should be substantially identical with the normal backward inclination of the connecting lever 21 in the middle of the group of these levers (as shown in Figure 1) and this angle is a little less than fifteen degrees from the vertical as heretofore described. 60

It is a peculiarity of my mounting that all the pins or rollers 22 at the upper ends of the levers 21 lie in a common vertical plane. This is indicated in dotted lines in Figure 1, wherein a circle indicating the pin 22 of a lever near one end 70 of the row is shown connected by a vertical dotted line with the pin 22 on the middle lever 21. It is also a peculiarity of my arrangement that the pins or rollers 23 on the lower ends of levers 21 are all in alignment, notwithstanding the pro- 75

gressively greater length of the lower arms of the levers 21 from the middle to the ends of the group.

The importance of this arrangement is found in the fact that it makes it possible to make all the cam slots 24 identical in all the finger key levers 16 of the same length—that is to say—in the same bank or row. By thus making all the key levers of each row interchangeable it is not necessary to identify the position of each in its row—as hitherto essential—it being only necessary to put a given lever into the right row, which is instantly determined by the length of the lever. This greatly facilitates assembling. This feature is exemplified in Figures 5 and 5a which show the slotted portions of any two key levers 16 of the same row, showing the identical shape and position, with respect to the lever, of the cam-slots 24.

20 Various changes may be made in this construction without departing from the scope of my invention, which is not limited to the details herein shown and described.

This application is a substitute for my previous application, Ser. No. 581,149, filed August 11, 1922.

What is claimed is:

1. In a typewriter action, a pivoted type bar, a swinging connecting lever mounted between its ends, said lever having a pin and slot connection with the type bar and having a pin at its lower end, and a key lever fulcrumed behind said connecting lever and having a cam lying normally against said pin and adapted to swing the lower end of said connecting lever backward to approximately the vertical line through its pivot when the key lever is depressed whereby the variation in the effective leverage of the shorter arm of the connecting lever is minimized.

2. A typewriter action of the character set forth in claim 1 hereof wherein the rear end of the type bar and the upper arm of the connecting lever swing together across a line joining their respective bearings, and wherein the operative cam surface of the corresponding key lever is shaped to produce a sufficiently accelerated swing in the connecting lever to overcome the unfavorable changes in leverage due to the pin and slot connection at the type bar and impart an accelerated movement to said bar during the latter part of its movement.

3. In a typewriter action of the character set forth in claim 1 hereof, a guide block for the connecting levers having parallel guide slots and a common bearing rod for the connecting levers, said rod being bent in the arc of a circle and being laid in openings in the guide block and passing through the connecting levers; the openings in the connecting levers being countersunk to permit them to swing in parallel planes in said guide slots on the curved rod as a bearing.

4. In a typewriter action of the character set forth in claim 1 hereof, a series of bearings for the connecting levers arranged in an upwardly concave curve lying in a plane inclined backward from the vertical.

5. In a typewriter action, a plurality of nested type bars converging to a common printing point, a plurality of pivoted connecting levers respectively connected therewith by direct pin and slot connections, and a key lever for each connecting lever, each connected by a direct pin and cam connection, all the functioning parts of the key levers in a row being identical in form and position so that all key-levers in a row may be as-

sembled with their connecting levers without differentiation.

6. In a typewriter action, type bars, key levers, and intermediate connecting levers each connected directly to a type bar and to a key lever, in combination with a common mounting for the connecting levers comprising bearings for said levers which lie in a curve whose plane is inclined backward at substantially the same inclination as that of the position of rest of the connecting levers at the middle of the series.

7. In a typewriter action, nested type bars and connecting levers directly connected therewith by pin and slot connections and having pins at their lower ends, said type bars and connecting levers being mounted so as to swing together across a line joining their respective bearings; in combination with key levers fulcrumed behind said connecting levers and having cams engaging the pins at the lower ends of the connecting levers whose operative surfaces are shaped to produce a sufficiently accelerated swing in the connecting levers to overcome the unfavorable changes in leverage due to the pin and slot connection at the type bar and impart an accelerated movement to said bars during the latter part of their movement.

8. In a typewriter action, type bars, connecting levers operatively connected therewith, a guide block for the connecting levers having parallel guide slots and a common curved bearing rod for the connecting levers, said rod passing through openings in the guide block and connecting levers; the openings in the connecting levers being countersunk to permit them to swing in parallel planes on the curved bearing rod as a bearing.

9. The combination, in a typewriter action, of a plurality of type-bars provided with operating arms, pivots for said type-bars arranged in a curve, said type-bars lying substantially horizontal in their retracted positions, a plurality of key-levers having pivots below and at the rear of the type-bar pivots and arranged with their key-ends in a plurality of rows, connecting-levers joining each key-lever with a type-bar-arm, a pin-and-slot connection between each end of a connecting-lever, and a key-lever and a type-bar-arm, pivots for said connecting-levers intermediate the ends of said connecting-levers arranged in a curve which lies in an inclined plane, said connecting-levers having arms of progressively increased length from the middle to the ends of the set, the arms of said connecting-levers from the middle to the ends of the set being of progressively decreased angularity with respect to vertical planes passing through and lengthwise of the pivotal bearings of the respective connecting levers, and the key-ends of the key-levers having substantially the same amount of depression-movement.

10. A combination according to claim 9, wherein in the ends of the connecting-levers move through arcs of substantially equal length.

11. A combination according to claim 9, wherein in the type-bar-arms move across a line joining the pivots of the type-bar-arms and of the connecting-levers, and said slots of the connection between the key-levers and connecting-levers are shaped to accelerate the movements of the type-bars in the latter part of their movements caused by the depression of the key-levers.

12. A combination according to claim 9, wherein in the pin-and-slot connections between the key-levers (of any set in which the key-ends are arranged in a row) and the corresponding connect-

75 70 75

ing-levers comprise identical slots in said row of key-levers.

13. A combination according to claim 9, wherein in the slots of the connection between the key-levers and connecting-levers are shaped to accelerate the movements of the type-bars in the latter part of their movements caused by the depression of the key-levers, all of said key-levers of any set in which the key-ends are arranged in a row 10 being identical.

14. A combination according to claim 9, wherein in the pins at the upper ends of said connecting-levers all lie in a common vertical plane and the pins at the lower ends of said connecting-levers all lie in alinement.

15. A combination according to claim 9, wherein in the ratio between the lengths of the arms of the connecting-levers on each side of their pivots is constant.

ANDREW F. MULHARE. 10
